AIRPLANE

Ralph L. Bayless and Ernest G. Stout, San Diego, Calif., assignors to Consolidated Vultee Aircraft Corporation, San Diego, Calif., a corporation of Delaware

Application October 24, 1949, Serial No. 5,676

Term of patent 14 years

(Cl. D71—1)

To all whom it may concern:

Be it known that we, Ralph L. Bayless and Ernest G. Stout, both citizens of the United States, residing at San Diego, in the county of San Diego and State of California, have invented a new, original, and ornamental Design for an Airplane, of which the following is a specification, reference being had to the accompanying drawings, forming a part thereof.

In the drawings:

Figure 1 is a bottom perspective view of an airplane, showing our new design;

Figure 2 is a side elevational view of the airplane;

Figure 3 is a top plan view; and
Figure 4 is a front elevational view thereof.
We claim:

The ornamental design for an airplane, substantially as shown.

RALPH L. BAYLESS.
ERNEST G. STOUT.
